(57) **CLAIM**

We claim the ornamental design for a pull, as shown and described.

DESCRIPTION

FIG. 1 is an elevated perspective view of the pull handle of the present claimed invention;

FIG. 2 is front view of the pull shown in FIG. 1;

FIG. 3 is an end view of the pull shown in FIG. 1, the opposite end side being identical thereto;

FIG. 4 is a side view of the pull shown in FIG. 1, the opposite side view being identical thereto; and,

FIG. 5 is a rear view of the pull shown in FIG. 1.

Features shown in broken lines in the drawings are not part of the claim.
